UNITED STATES PATENT OFFICE.

ALFRED BLANCHARD, OF WARE, MASSACHUSETTS, ASSIGNOR TO OTIS COMPANY, OF WARE, MASSACHUSETTS, A CORPORATION OF MASSACHUSETTS.

YARN-CONDITIONING MACHINE.

Application filed April 24, 1926. Serial No. 104,328.

My invention relates to a device for conditioning yarn and particularly rayon and celanese yarns to improve their knitting qualities. It has been found in the knitting 5 of these yarns that they can be knit much more satisfactorily and with less trouble from splitting and breakage, and from fibres which wrap around the needles of the machine, if the yarns are conditioned by being subjected to the action of steam or water 10 vapor and are treated with a vegetable oil like olive oil just before being knitted. As far as is known to me there has not been any satisfactory device for attachment to a knitting machine which will properly condition 15 the yarn. As is well known to those skilled in the art, the yarn should be treated exactly the right amount as either too much or too little treatment injuriously affects the 20 condition of the yarn for knitting. Furthermore, it is very important that the yarn be conducted along a path such that the strain on the yarn will be reduced as much as possible and so that there shall be no corners or sharp angles which are likely to injure the yarn or break it. The device must 25 also be constructed so that it can be quickly and easily threaded up and so that when a yarn breaks it will not contact with other 30 yarns and tangle some or all of them.

In the device embodying my invention I provide a steam chamber and an oil chamber 35 the whole being located inside the area defined by the several yarns as they run from the cones of the knitting machine to the yarn guides above them. From the cones, the yarn passes through the several yarn guides, then down through cylindrical chambers in the conditioning device being 40 there subjected to the action of steam or water vapor, thence over a wick communicating with the oil pan and thence through the tension devices directly to the needles. The device takes advantage of the natural path- 45 way of the yarn and delivers the perfectly conditioned yarn directly to the needles before any change in the condition takes place. Each yarn is separated from the others so 50 that there is no tangling when one breaks in the device. By the use of the device embodying my invention much less oil can be employed, the goods are more uniform and smoother, there is less breakage of needles and the machine can be run at a higher rate

of speed and is not stopped as frequently 55 on account of troubles arising from the condition of the yarn.

The invention will be fully understood from the following description when taken in connection with the accompanying drawings 60 and the novel features thereof will be pointed out and clearly defined in the claims at the close of this specification.

In the drawings:

Fig. 1 is a side elevation of the upper part 65 of a knitting machine to which is applied the attachment embodying my invention.

Fig. 2 is a section on line 2—2 of Fig. 3.

Fig. 3 is a top plan view of the device shown in Fig. 2.

Fig. 4 is a section on line 4—4, Fig. 1.

Fig. 5 is a horizontal section of a modified form of the device embodying my invention.

Referring now to the drawings and particularly to Fig. 1:

At A is shown conventionally the cylinder or knitting head of a knitting machine of ordinary construction. At B is shown the cone supporting frame mounted on a central rod C which also carries the top 80 yarn guides D and central yarn guides G. The cones of yarn are shown at E and the yarn at F.

Inside the space defined by the several yarns F is placed the yarn conditioner 85 embodying my invention. This yarn conditioner will be more fully understood by reference to Figs. 2 and 3. It includes a base 11 containing an oil chamber 12, and an upper section 13 containing a steam chamber 90 14, the lower part of which is cylindrical and the upper part of which is preferably formed in the shape of a frustum of a cone. The steam chamber is closed by a top 15. Centrally located of the device is a pipe 16 95 through which the upright rod C, which supports the upper yarn guides, passes. The conical portion of the steam chamber 14 is slotted as shown at 17—17 with a series of upwardly inclined slots and these slots are 100 covered or enclosed by tubular members 18 which form auxiliary steam chambers lying on the outside of the conical portion. This construction will be clearly shown by reference to Fig. 4. These cylindrical members 18 are conical in shape at the upper end as shown at 40, see Fig. 3. Both upper and lower ends are provided with porcelain yarn

guides 6. This construction is such that the device can be threaded easily by the use of a wire or "snake" which is centered by the conical upper end 40. Thus, in threading the device applicant inserts a "snake" or wire through the lower yarn guide 6 in each of the members 18, and this wire is centered by the conical upper end 40, so that it will pass through the yarn guide 6. The yarn 10 is then attached to the end of the wire or "snake" projecting through the upper end of the member 18 and is drawn down through that member.

Steam is supplied to the steam chamber 14 15 by the inlet pipe 23 and the condensation is removed by a drip pipe 24 which passes down through the oil chamber 12.

The oil chamber 12 contains a suitable supply of proper oil for conditioning the particular yarn to be knit and is provided with a series of wicks 7 which extend into the interior of the oil pan and lie over its upper outer edge in the path of the yarn as it comes out of the lower yarn guide 6. At 26 is shown another yarn guide which prevents the yarn from being displaced laterally and working off the wick. This yarn guide is also located so that the pressure of the yarn on the wick is sufficient to oil it properly but 30 not enough to cut into the wick.

In the operation of the device embodying my machine, the pan 12 is filled with oil which is drawn up by capillary attraction through the wicks 7. The yarns from the 35 cones E pass over the top yarn guides D then through the center yarn guides G. Thence it passes downwardly to the yarn guides 6 which are located at the upper ends of the auxiliary chambers 18. As the yarn passes 40 through the chambers it is subjected to the softening action of the steam vapor. The yarn then passes out from the lower yarn guides 6 over the wicks 7 and through the yarn guides 26 and thence directly to tension 45 devices, not shown, and to the needles.

By making the auxiliary chamber 18 the proper length and by regulating the temperature of the steam or water vapor in the steam chamber 14, the yarn will be satisfactorily conditioned without being softened too 50 much which has heretofore been a serious objection with steam devices for conditioning rayon and celanese yarns. The oil in the oil chamber is heated by the steam from the 55 steam chamber which thus increases the tendency of the oil to flow and improves the operation of the machine, but the oil is not mixed with the condensation from the steam and the full benefit of the oil is obtained. 60 Since each yarn is contained in a separate steam chamber 18 while it is being steamed, no tangling with the other yarns occurs, if the yarn breaks. It will also be seen that the several steam chambers and the oil 65 wicks are in the natural path of the yarn

from the cones to the needles, and that the yarn passes directly from the conditioning device to the needles while it is still in the best condition for knitting.

In Fig. 5 I have shown on a smaller scale 70 a modified form of the device embodying my invention. In this form of the device there is a base 50 containing the oil chamber, a central cylindrical steam chamber 51 and a series of auxiliary steam chambers 52 which 75 are connected to the central chamber 51 and supported by a radial brace 53. The steam passes from the central steam chamber to the auxiliary steam chambers in the same way as in the preferred form of my device and 80 several yarns are sufficiently enclosed by the auxiliary chambers to prevent tangling in case of breakage of any of the yarns.

What I claim is:

1. The conditioning device for a machine 85 of the character described comprising a plurality of separate steam chambers one for each thread to be conditioned, a main steam chamber supplying steam to said separate chambers, and an oiling device supplying oil 90 to the yarn as it emerges from said separate steam chambers.

2. The conditioning device for a machine 95 of the character described comprising a plurality of separate steam chambers one for each thread to be conditioned, a main steam chamber supplying steam to said separate chambers and a wick feed oiling device supplying oil to the yarn as it emerges from said 100 separate steam chambers.

3. The improved conditioning device for the machines of the character described comprising a plurality of steam chambers and an oil chamber, yarn guides directing the yarns through the steam chambers, and 105 wicks each having one end in the oil chamber and another portion thereof in the path of the yarn as it emerges from the steam chamber.

4. The conditioning device for a machine 110 of the character described comprising a plurality of separate steam chambers, one for each thread to be conditioned, a main steam chamber supplying steam to said separate chambers, an oil chamber separate from the steam chambers but heated thereby, and wick oilers taking oil from said chamber applying it to the yarns as they emerge from the steam chambers.

5. The conditioning device for a machine 115 of the character described, comprising a plurality of separate steam chambers, one for each thread to be conditioned, and provided with a yarn guide in the end thereof, the end provided with said yarn guide having an interior conical surface adjoining the thread opening to facilitate threading the device.

6. The improved conditioning device for machines of the character described comprising a steam chamber and an oil chamber,

a series of auxiliary chambers communicating with the steam chamber and each being provided with yarn guides for directing the yarn through said smaller steam chambers, 5 and wicks the ends of which are in the oil chamber and portions of which overlie the edge of the oil chamber in the path of the yarn as it emerges from the said smaller chambers.

10 7. The improved conditioning device comprising a frusto-conical steam chamber provided on the exterior thereof with a series of smaller steam chambers communicating with the main steam chamber, an oil chamber beneath said steam chamber, wicks having their inner ends in the oil chamber and the outer portions thereof overlying the upper edge of the oil chamber, yarn guides in the upper and lower ends of the auxiliary chambers, the whole being so constructed that each of the several yarns to be conditioned will each pass through one of the auxiliary chambers and on emerging therefrom will pass over one of the said wicks on its way 25 to the needles of the machine.

8. In combination with a knitting machine which includes cone supports, upper yarn guides and needles and a central rod to support the upper yarn guides, a device including a steam chamber and an oil chamber surrounding said central rod, said steam chamber being provided with yarn guides to direct the yarn into and out of said steam chamber and said oil chamber being provided with wicks to apply oil to the yarn as it emerges from the steam chamber, the whole being located above the cylinders of the knitting machine so that the yarn will pass from the cones over the upper yarn 30 guides through the steam chamber over the wicks and directly to the needles of the knitting machine.

9. In combination, means for transferring yarn in a continuous length from one place to another, means for heating and slightly moistening said yarn during its passage, and means for applying an oil to the yarn immediately after the heating and moistening thereof, substantially as described.

50 10. The method of treating yarn which consists in moving the same in a continuous length from one place to another, heating and moistening the yarn during its movement, and wiping said yarn, after the heating and moistening thereof, against an oil

saturated member, substantially as and for the purposes described.

11. In combination, a machine adapted to carry a bobbin of yarn or like material and to use yarn unwound from said bobbin, combined with a hollow member through which the yarn passes, said member having guides in substantially opposite sides thereof for the passage of the yarn, means for conducting steam to the interior of said member and 60 means for applying an oil to the yarn immediately after it is passed from said hollow member.

12. In combination, with a knitting machine having a support for a bobbin of yarn, 70 the yarn being transferred from said bobbin to said knitting machine, of an elongated tubular member through which the yarn passes lengthwise, guides for the yarn in opposite ends of said member, means for supplying steam to the interior of said member, and an oil saturated wick disposed closely adjacent to the outlet of said member against which the yarn bears to have wiping contact therewith, as it passes to the 75 knitting machine, substantially as described.

13. In a knitting machine having a support for a plurality of bobbins of yarn, a hollow member through which yarn from all of the bobbins passes to the knitting machine, said member having a plurality of pairs of guides, one pair for each yarn passing to the machine through which the yarn passes thereby traversing the hollow member, means for supplying steam to the interior of said member, a pan adapted to hold an oil maintained in liquid condition from the heat given off by said steam, said pan being located at the outlet side of said member, and wicks, one for each yarn passing from the member, having one end immersed in said oil and the opposite end positioned so that its respective yarn bears against it as it passes from said hollow member to the machine.

14. The method of treating yarn for knitting which consists in moving a length of yarn lengthwise from one point to another, subjecting the yarn, during a portion of its movement, to the action of steam, and immediately applying oil to the yarn after it has been heated and moistened by the steam.

In testimony whereof I affix my signature.

ALFRED BLANCHARD.
